CASING PERFORATOR

Walter L. Church, Houston, Tex.

Application August 21, 1933, Serial No. 686,065

7 Claims. (Cl. 81—188)

This invention relates to a casing perforator.

An object of the invention is to provide a tool of the character described specially designed for use in perforating casing or other pipe in a well bore.

Another object of the invention is to provide a tool of the character described that may be set in neutral or inoperative position for going into the well and which may then be tripped and rendered operative whereby the casing or other pipe in the well may be perforated to permit the inflow of fluid into the casing or perforated pipe.

A further object of the invention is to provide a tool of the character described which may be rendered inoperative or inactive while in the well to the end that it may be further lowered after a perforating operation has been completed and then tripped and rendered active for the further perforation of the casing or pipe.

A still further object of the invention is to provide a tool of the character described through which fluid may be circulated from a pump at the ground surface and equipped with means for closing the fluid passageway and stopping the pump at each perforating operation.

With the above and other objects in view the invention has certain relation to certain novel features of construction, operation and arrangement of parts, an example of which is given in this specification and illustrated in the accompanying drawings, wherein:

Figures 1, 2 and 3 show vertical, sectional views of an upper, intermediate and lower section of the tool, Figure 3 showing the tool partly in elevation.

Figure 4 shows a side view of the tool shown in inactive position.

Figure 5 shows a side view thereof in active position.

Figure 6 shows a cross sectional view taken on the line 6—6 of Figure 1.

Figure 7 shows a cross sectional view taken on the line 7—7 of Figure 2.

Figure 8 shows a cross sectional view taken on the line 8—8 of Figure 3.

Figure 9 shows a cross sectional view taken on the line 9—9 of Figure 3, and

Figure 10 shows a fragmentary elevational view of the perforator body.

Referring now more particularly to the drawings wherein like numerals of reference designate similar parts in each of the figures, the numeral 1 designates the perforator body connected onto the upper end of which there is the

shell 2 of tubular formation and having the inside annular shoulder 3 at its lower end.

Screwed into the upper end of the shell there is the gland 4 having the inside vertical grooves 5. There is a mandrel 6 which works through the gland 4 and has the vertical ribs 7 thereon which work in the grooves 5. This mandrel is tubular and its upper end is connected to an operating string 8 by the coupling 9.

The lower end of the mandrel 6 has an enlarged hammer-like head 10 which fits loosely in the shell 2.

Depending from the body 1 there is a shaft 11 whose upper end has the flange 12 bolted to said body by means of the bolts 13.

Threaded onto the lower end of the shaft 11 there is a guide 14 whose lower end is rounded off or of oval formation. The upper end of the guide 14 is reduced and provided with external coarse threads 15. There is a tubular cage 16 around the shaft 11 whose lower end has the internal coarse threads to receive the threads 15. The upper end of the guide 14 and the lower end of the cage 16 are provided with the opposing oppositely directed shoulders 17 and 18 arranged to interengage when the cage is screwed onto said guide to prevent their intermeshing threads from making up too tight.

Adjacent and above said cage there is a swivel block 19 around the shaft 11 and closely surrounding said shaft there is a sectional sleeve 20 whose lower end has the external annular flange 21 which fits into an inside annular groove 22 in the upper end of said cage and the upper end of said sleeve has an annular external flange 23 which fits into an inside annular groove 24 in the swivel block 19 whereby said cage and block are maintained in assembled relation but are permitted to rotate one relative to the other.

The upper end of the shaft 11 is tubular, that is provided with a deep socket 25 radiating from which are the elongated slots 26.

Within the socket 25 there is a plunger 27, whose lower end has a cross pin 28 which works through the slots 26 and whose ends are journaled in bearings in the swivel block 19.

The cage 16 has the longitudinal radially extending slots 29 in which the friction dogs 30 are mounted and opposite these slots said casing has an inside tubular liner 31 which is secured in place by the upper and lower bolts 32, 33 which are screwed through the cage into said liner. Interposed between the liner 31 and the respective friction dogs are the coil pressure springs 34 which hold said dogs yieldingly out-

wardly. The outward movement of said dogs is limited by the engagement of its ends with the heads of the respective bolts 32, 33.

The lower end of the perforator body 1, at one side, has the deep relatively narrow, longitudinal groove 35, which is widened downwardly and opposite said groove has a longitudinal external bearing rib 36.

Slidably mounted in said bearing groove 35 there is a block 37 forming a cutter carrier. The outer side of this carrier is provided with a narrow cutter bearing 38 whose upper side forms a shoulder 39, extending out approximately at right angles to the axis of the perforated body and whose lower side 40 diverges from said shoulder downwardly. A punch like cutter 41, has its outer end pointed as at 42 and its inner end is seated in the bearing 38 and is mounted on the cross pin 43. The inner end of the cutter 41 is rounded off and the bottom of the bearing 38 is correspondingly shaped to receive said rounded off inner end of the cutter. The ends of the pin 43, on which the cutter 41 is mounted, work in the side slots 44, 44, said slots 44 being arranged diagonally with respect to the vertical axis of the body and being arranged approximately parallel with the inner wall 45 of the groove 35.

As stated the operating stem 8 and mandrel 6 are tubular, thus providing a passageway for fluid and this passageway continues on down through the lower end of the shell 2 and through the upper end of the perforator body and terminates in the upper end of the groove 35 at the point 46.

In operation the tool is set, as illustrated in Figure 4, that is, the upper end of the guide 14 is screwed into the lower end of the cage 16 with the cutter carrier 37 at the lower end of the groove 35. The cutter 41 will be in its lower position as shown in Figure 2 out of contact with the casing 47 to be perforated. When the tool has been lowered to the desired location the operating stem 8 may be turned to the right to unscrew the guide 14 from the cage 16. During this operation the cage 16 will be held stationary by the frictional contact of the dogs 30 with the casing 47.

As noted in Figure 8 the outer surfaces of these dogs are convex to conform to the curvature of the casing so as to provide a maximum gripping surface. When the guide 14 is unscrewed from the cage 16 the operating stem may be lowered, but the cage 16 and the swivel block 19 will be held against downward movement by the frictional engagement with the dogs 30 with the casing. Upon such downward movement the block 37 will contact with the upper end of the plunger 21, which is also held stationary and said block 37 and the cutter 41 mounted therein will be held against downward movement, while the perforator body 1 moves downwardly and the inner wall 45 of the groove 35 of said body will operate upon the block 37 with wedge like effect moving said block and cutter outwardly radially until the point 42 of the cutter 41 engages the wall of the casing 47. Thereupon the operating stem 8 may be elevated and dropped alternately, the head 10 striking the shoulder 3 and gradually driving the perforator body downwardly relative to the block 37 with wedge-like effect, forcing said block further outwardly and causing the blade 41 to gradually assume a radial direction and to force itself through the wall of the casing thus perforating the same. Eventually the block 37 will reach the

upper end of the groove 35 as shown in dotted lines in Figure 2 thus closing the passageway to the cutter body and stalling the pump so that the operator may know the tool is working properly and that the pipe has been perforated. Thereupon the operating string 8 may be elevated to elevate the perforator body relative to the block 37, thus causing a withdrawal of the blade 41 from the perforation made by it and the tool may then be gradually rotated and elevated and the operation above described repeated until the casing has been perforated the number of times desired and if desired, the casing may be perforated on all sides from the point of beginning upwardly as far as necessary.

If it should be desired to reset the tool so as to go deeper into the well for perforating operations, the operating stem 8 may be elevated and turned to the left so as to screw the guide 14 back into the lower end of the cage 16, and the tool thus reset or rendered inactive until it is adjusted to the desired place for resuming operations.

The drawings and description disclose what is now considered to be a preferred form of the invention by way of illustration only, while the broad principle of the invention will be defined by the appended claims.

What I claim is:

1. A pipe perforator shaped to be lowered into a pipe in a well and having a passageway for liquid and comprising a perforator body, a carrier movably mounted on the body, a blade on the carrier, said body and carrier having coacting parts effective to move the carrier outwardly to engage the blade with the pipe upon a longitudinal movement of the body relative to the carrier in one direction, impact means for effecting the further longitudinal movement of the body relative to the carrier whereby the blade is forced through the wall of the pipe and the carrier is relatively moved to a position to close said passageway.

2. A pipe perforator shaped to be lowered into a pipe in a well and comprising a body, a carrier mounted for longitudinal movement relative to the body provided with a bearing having an upper radial shoulder and whose lower side diverges downwardly from the shoulder, a cutter whose inner end is pivotally mounted in said bearing in the carrier, said body and carrier having co-acting parts effective to move the carrier radially upon longitudinal movement of the body relative to the carrier, an anchor having grip means engageable with the pipe, means connected to the body and to the anchor whereby the body is normally held against downward movement relative to the anchor, said connecting means being releasable to permit the body to move downwardly relative to the anchor, and means on the anchor for engaging and holding the carrier against downward movement upon downward movement of the body whereby said carrier and cutter are forced outwardly to force the cutter through the wall of the pipe.

3. A pipe perforator shaped to be lowered into a pipe in a well and comprising a perforator body, an anchor engageable with said pipe, means connected to the body and to the anchor and normally preventing the downward movement of the body relative to the anchor, said means being releasable to permit such downward movement of the body, a carrier movably mounted on the body having an outwardly flared bearing, a blade whose inner end is pivoted in the bearing in the

carrier, means on the anchor to maintain the carrier against downward movement, said body and carrier having coacting parts effective to move the carrier outwardly to engage the blade 5 with the pipe upon such downward movement of the body, and impact means to drive the body further downwardly to force said blade through the wall of the pipe.

4. A pipe perforator shaped to be inserted into 10 a pipe and comprising an operating string, a perforator body thereon, an anchor engageable with the pipe, means connecting the body and anchor and normally preventing their relative longitudinal movement said connecting means being releasable to permit such relative movement, a carrier 15 movably mounted on the body, a blade on the carrier, means on the anchor arranged to hold the carrier against longitudinal movement relative to the pipe upon initial longitudinal movement of the body, said body and carrier having coacting parts effective to move the carrier outwardly upon such initial movement to engage the cutter with the pipe, said string and body having a passageway for liquid therethrough, and means 20 for imparting a final longitudinal movement to the body to effect a final relative movement of the carrier into position to close the passageway and force the cutter through the wall of the pipe.

5. A pipe perforator shaped to be lowered into 25 a pipe in a well and comprising an operating string, a body thereon, an anchor engageable with said pipe, a carrier on the body, a blade pivoted on the carrier, said carrier and blade being normally inactive but being relatively movable, with respect to the body, into active position to force the blade through the wall of the pipe, a stop on the carrier to limit the upward movement of the blade relative to the carrier, means connecting the body and anchor and normally preventing the downward movement of the body relative to the anchor to maintain the carrier and blade in said inactive position, said connecting means being releasable to permit the downward movement of the body relative to the anchor, a plunger arranged to arrest the downward movement of the carrier upon such downward movement of the body, said body and carrier having cooperating parts effective to move the carrier and blade outwardly into said active position upon such downward movement of the body, said connecting means being arranged to be reconnected by manipulation of the string to render said carrier and blade inactive.

6. A pipe perforator shaped to be lowered into

5 a pipe in a well and comprising an operating string, a body thereon, an anchor engageable with said pipe, a carrier on the body having a blade bearing whose upper side is approximately radial and whose lower side diverges downwardly from said upper side, a blade whose inner end is pivotally mounted in said bearing, said carrier and blade being normally inactive but being movable as a unit relative to the body into active position to force the blade through the wall of the pipe, means connecting the body and anchor and normally preventing the downward movement of the body relative to the anchor to maintain the carrier and blade in said inactive position, said connecting means being releasable to permit the 10 downward movement of the body relative to the anchor and having an actuator therein to arrest the downward movement of the carrier upon such downward movement of the body, said body and carrier having cooperating parts effective to move the carrier and blade outwardly into said active position upon such downward movement of the body, said connecting means being arranged to be reconnected by manipulation of the string to render the carrier and blade inactive.

7. A pipe perforator shaped to be lowered into 15 a pipe in a well and comprising an operating string, a body thereon, an anchor engageable with said pipe, a carrier on the body having a blade bearing whose lower side declines outwardly relative to the vertical axis of the body, a blade whose inner end is pivotally mounted in said bearing, a stop above the bearing arranged to limit the upward movement of the blade to an approximately radial position relative to the body, said carrier 20 and blade being normally inactive but being movable as a unit relative to the body into active position to force the blade through the wall of the pipe, means connecting the body and anchor and normally preventing the downward movement of the body relative to the anchor to maintain the carrier and blade in said inactive position, said connecting means being releasable to permit the 25 downward movement of the body relative to the anchor and having an actuator therein to arrest the downward movement of the carrier upon such downward movement of the body, said body and carrier having cooperating parts effective to move the carrier and blade outwardly into said active position upon such downward movement of the body, said connecting means being arranged to be 30 reconnected by manipulation of the string to render the carrier and blade inactive.

WALTER L. CHURCH.
